Inventor.

Oliver E. Pillard.

United States Patent Office.

OLIVER E. PILLARD, OF NEW BRITAIN, CONNECTICUT, ASSIGNOR TO FRED ERICK H. NORTH, OF SAME PLACE.

Letters Patent No. 97,550, dated December 7, 1869.

IMPROVEMENT IN PERMUTATION-LOCKS.

The Schedule referred to in these Letters Patent and making part of the same.

To all whom it may concern:

Be it known that I, OLIVER E. PILLARD, of New Britain, in the county of Hartford, and State of Connecticut, have invented a new and useful Improvement in Combination-Locks; and I do hereby declare that the following is a full, clear, and exact description of the same, reference being had to the accompanying drawings, making a part of this specification, in which—

Figure 1 is a side elevation of my invention, the cap-plate being removed.

Figure 2 is a side elevation of the latch, viewed from the back side.

Figure 3 is an edge view of the exterior parts, viewed from the under side.

Figure 4 is a side elevation of the shaft for operating the lock.

Similar letters of reference indicate like parts.

My invention consists in the peculiar arrangement of the latch with the tumblers, so that the latter shall not rotate as the bolt is moved.

A designates the case or shell.

B designates the latch. The back side is provided with a longitudinal recess, *a*, in which is fitted the slide *C*.

Slide *C* is provided with an arm, *b*, and pin *c*.

The position of the slide *C* and pin *c*, in fig. 1, is indicated by broken lines.

Latch *B* is also provided with an arm, *d*, and is pivoted directly to the case *A*, and in front of the bolt *D*.

The pin *c* extends into the slot *e*, in the bolt *D*, which slot allows the pin to play vertically, so that the latch *B* and slide *C* may be raised when desired, but as the bolt *D* is moved, the pin moves the slide *C* laterally, while the latch *B* remains motionless.

To the shaft *E* there is attached a gear, *F*, meshing into intermediate gear *G*, which meshes into another gear, under and secured to the throwing-disk *H*.

The arm *b*, of the slide *C*, when the lock is unlocked, rests in a slot in disk *H*.

By turning the shaft *E*, the bolt *D* can thus be thrown out and in.

Four tumblers, with a slot in the periphery of each, are placed one in front of the other, and all in front of the disk *H*; but to better show the disk, the tumblers are not shown, while their outlines are traced in the broken lines *I*.

As the latch *B* never moves laterally, and the arm *d* rests in the slot in the tumblers *I*, the tumblers cannot revolve while the bolt *D* is being thrown.

The red lines in fig. 1 indicate the position of the parts with the bolt *D* thrown outward.

To lock the device, the shaft *E* is rotated quickly, so as to throw the bolt out with considerable force, when the arm *b* will raise out of the slot in the disk *H*, and rest on the periphery of the same, which will cause the latch *B* to raise with its end immediately back of the stud *g*, on the bolt *D*.

In any attempt to slide the bolt back by pressure on its end, it will be seen that the arrangement of the latch *B* is such that all of the strain is exerted on the case *A* and stud *g*, one of which must fail before the bolt can be driven back by pressure on its end.

By bringing the slots in the tumblers *I* all at the same time under the arm *d*, the latch *B* will fall, and allow the bolt *D* to withdraw.

On the inside of the lock, I insert three or more screws, *i*, which screws are of such length as to extend, when desired, to the outside of the lock. (See fig. 3.)

The object of the screws *i* is to provide a cheap and convenient way to draw the hub *L* firmly into the door to which the lock is to be attached.

A tapering hole is made in the door, to correspond with the shape of the hub *L*, and should fit the hub *L* so snugly that the effect of blows, or pressure on the end of shaft or hub, will be received by the door instead of the lock.

Simply placing the hub in the door is an old device, but such a fit as is desirable is not always easily secured.

The hub *L* is unscrewed from the lock and passed through the hole in the door, and then again screwed into the lock, which is placed on the back side of the door.

The screws *i* are then extended until the hub *L* snugly fits the hole through the door.

The lock can then be secured by bolts, while the hub *L* remains properly fitted in place.

The shaft *E* is provided with two tapering shoulders, *m m'*.

The bearing in the hub *L*, indicated by broken lines, fig. 3, is of a shape to fit the inside shoulder *m'*.

The shaft *E* is partially cut into, so that on breaking the same, it will break outside of both shoulders *m m'*.

The expert, in lock-picking, will then attempt or desire to remove the shaft by drilling it out, but as it freely revolves, he must secure it firmly in its place before he can succeed in drilling it.

By making the inside shoulder *m'* tapering, blows on the end of the shaft will not upset the same, or destroy the freedom with which it revolves.

The outside shoulder being tapering, it will also be much more difficult to prevent the rotation of the shaft by upsetting the end with a cold-chisel or otherwise, than it would be if the shoulder were square.

The latch *B* and slide *C* are the only new elements of this invention.

What I claim as new, and desire to secure by Letters Patent, is—

The latch *B*, when secured to the case *A*, and provided with the slide *C*, arranged to slide longitudinally with the same, substantially as described.

OLIVER E. PILLARD.
